UNITED STATES PATENT OFFICE.

FRANK W. WOOD, OF NEW YORK, N. Y., ASSIGNOR TO CHARLES CORY & SON, INC., OF NEW YORK, N. Y., A CORPORATION OF NEW YORK.

SIGNAL.

1,194,914.

Specification of Letters Patent. Patented Aug. 15, 1916.

Application filed October 5, 1914. Serial No. 865,047.

To all whom it may concern:

Be it known that I, FRANK W. WOOD, a citizen of the United States, residing at New York, in the county of New York and State of New York, have invented new and useful Improvements in Signals, of which the following is a specification.

This invention relates to new and useful improvements in signals and particularly to fluid operated signals such as whistles.

The invention is particularly applicable to whistles used aboard ship.

A principal object of the invention is to produce a signal which can be operated in the ordinary way by hand, but which is associated with electrically controlled means for independently actuating the whistle.

A further object of the invention is to provide automatic means independent of the ordinary hand operated mechanism for enabling the whistle to be sounded periodically.

A further object of the invention is to provide an improved arrangement for effecting the automatic sounding of the whistle at regular time intervals by electrical means avoiding the necessity for a specially constructed clock motor.

A further object of the invention is to provide an arrangement enabling the whistle to be controlled from several points, for example, as on board ship, where such an arrangement enables the whistle to be controlled from the pilot house and from both ends of the bridge.

The invention consists in those features and combinations of parts to be described more fully hereinafter, all of which contribute to produce an efficient signal.

A preferred embodiment of my invention will be particularly described in the following specification while the broad scope of my invention will be pointed out in the appended claims.

In the drawings:—Figure 1 is a side elevation showing a portion of a whistle broken away and indicating part of the controlling apparatus for the whistle in longitudinal section. Fig. 2 is a plan of a motor and its contiguous parts for operating the whistle automatically. Fig. 3 is a cross section of the inclosing box of the motor shown in Fig. 2, certain parts being broken away.

Fig. 4 is a front elevation of a switch box for controlling the signal. Fig. 5 is a sec-

tion through the switch box illustrating the arrangement of the parts therein.

Referring more particularly to the parts, 10 represents a whistle or other signal of any suitable form which may be fluid-operated, for which purpose the pipe connection 10^a upon which the whistle is attached is provided with valve means 11 including a disk valve normally held on its seat by a spring 12. This valve 11 is operated either manually or electrically, but is adapted to be opened by steam pressure which is adapted to enter into the outer end of the steam chamber 14 in which moves an actuator preferably in the form of a piston 13, said piston 13 having a stem 15 which passes through the end wall or head 16 of the chamber. The end of this stem 15 rests against the face of the valve 11 so that if the steam or other fluid is admitted to the chamber 14 through port 20, the valve 11 will open and permit steam to flow directly through port 21 and past the valve means 11 into the whistle.

In order to control the admission of fluid to the piston or actuator 13, I prefer to provide auxiliary valve means 17 which is normally held on its seat by a spring 18, said valve having a stem 19 which extends longitudinally along the side of the case 22, being guided in suitable lugs 34 so that the outer end of said stem lies adjacent to the short arm of a hand operated lever 24, said lever having its fulcrum on the post 23 at the outer head 37 of the case. The long arm of this lever is provided with a cord 25 which is connected with an ordinary hand pulled device to enable the whistle to be blown at will.

In order to adapt the auxiliary valve 17 to be opened by electrically controlled means, I prefer to form the case 22 in the shape of a hollow cylinder, in the interior of which I place an electromagnet 26, preferably of the iron clad type, the coils of which are disposed around a suitable core 36 and within a metal shell 35. The case 22 is preferably provided with screw threads 38 enabling it to be attached in the end of chamber 14.

Mounted to slide in the inner end of the case, I provide an armature 27 which is preferably provided with suitable means for guiding it on the core 36, for which purpose I prefer to provide the inner side of the ar-

mature with a pin 28 which fits neatly in a bore in the core 36, said bore carrying a spring 33 which moves the armature away from the magnet whenever the magnet becomes deenergized. On the side of the armature away from the magnet another guide pin 29 is formed which moves in a suitable drilled hole in the inner head of the case. Pivotally attached loosely to the armature on its inner side there is a lever 30 having its fulcrum on a pin 30^a, and beyond this pin 30^a, the lever is formed with forks 31 which straddle the stem 19 and rest against the face of a collar 32 formed on this stem.

When the magnet 26 is energized, evidently the armature 27 will be attracted and the forks 31 will move the stem 19 toward the left, as viewed in Fig. 1, and this will open the auxiliary valve 17 and operate the signal. Evidently the lever 24 or the lever 30 can operate the whistle independently of each other.

I shall now describe the means for controlling the circuit through the magnet 26, which circuit passes through the conductors 56 and 57 which are connected with the opposite ends of the magnet. For this purpose, I prefer to provide an arrangement such as that illustrated diagrammatically in Fig. 1. This apparatus is such as to enable the magnet to be operated at will, or if desired, it can be energized periodically by automatic mechanism, which automatic mechanism is also preferably controlled electrically. As such automatic mechanism for operating whistles must operate to sound the whistle at regular time intervals to meet the marine rules, it is necessary to get substantially the effect of a clock mechanism. I

accomplish this in a very simple way by providing an ordinary electric motor, and arranging apparatus to be driven from it in such a way that the final driven shaft of the timing device rotates at a speed of one revolution per minute. With this arrangement, by placing a cam on this shaft, I can readily arrange to sound the whistle once in a minute, and by changing the length of the projecting face or cam tooth, I can readily change the length of time or number of seconds during which the whistle will sound.

Such a motor as I describe is indicated diagrammatically at 49, said motor having the shaft 51 and including suitable change speed mechanism, for driving the cam 50. The cam 50 controls a switch member 53 which closes the automatic circuit.

60 The energizing of the magnet 26 may be controlled from any number of points such as the three points 39, 40 and 41. The point 39 is supposed to be in the pilot house or conning tower of the ship, or at any other point of control. The points 40 and 41 may

be at the ends of the bridge. As indicated in Fig. 1, if the arm or switch member 42, operated by the handle 76, is moved to the right, its contact or end 45 may be brought in contact with the contact 47, and mechanically closes the following circuit, which circuit energizes the electromagnet 26 and keeps the whistle sounding until the arm 42 is moved again to mechanically open the circuit; double switch 63 having been closed, the current passes in by the line wire 62 through fuse 60 and conductors 59 and 48, pivot 48^a, thence by arm 42 and contact 47 to conductor 44 and conductor 56 through the coil of magnet 26 returning by the wire 57 to 68 and thence by fuse 58 through the line wire 61. If the whistle is to be sounded automatically, the lever 76 is moved in the opposite direction, that is, toward the left until contact 45 comes against contact 46. This will close a second circuit; wire 62 through switch 63, fuse 60, conductor 59, conductor 48, pivot 42^a, arm 42, contact 46, conductor 43 and through 43^a to motor terminal 69 and thence through the motor to 90 motor terminal 66, and then by conductor 67 through 68 and the fuse 58 to wire 61. This will start up the motor and will drive the cam 50; whenever the cam tooth 52 shoves the switch lever 53 toward the right, a second path for the current will be formed around the motor, from the point 70 to contact 65, through lever 53, conductor 73 to the point 72 and from this point by a conductor 55 to 74; from 74 the current will 100 pass along the conductor 56 through the electromagnet 26 and return by contact 57 to the point 68 and then out to the line wire 61.

As shown in Fig. 4, the cover 39^b may indicate the proper direction of movement of the lever 76.

I shall now describe the preferred construction and arrangement of the motor and the change speed mechanism for driving the timing device of which the cam 50 forms a part.

The shaft 51 of the motor preferably carries a worm 85 which meshes with a worm wheel 86 on the shaft 87, and the shaft 87 carries 115 a worm 88 which drives a worm wheel 89 on the shaft 90, said shaft 90 carrying the aforesaid cam 50 and being mounted at its outer end in a suitable bracket 91. The worms and worm shafts are arranged so that the shaft 90 will make one revolution per minute. With this arrangement it will be evident that the length of the high cam face 52 will determine the length of time, or number of seconds the whistle will sound, 125 and it will be evident that by substituting cams of different kinds, any number of different lengths of time of sounding can be automatically given.

On the base 81 for the motor 64 and ad- 130

jacent to cam 50, I provide the switch 53 which is pivoted at 53^a and normally held up by an insulated spring 54 so that the switch plates 65^a are held out of contact with plate or contact 65. In order to prevent 5
sparking, I prefer to provide auxiliary carbon contacts 65^b and 65^c, the former of which is carried on the plate 65^d. The switch is normally open; in the operation of the 10
switch when the cam arrives at the proper position it strikes projection 53^b on the switch arm 53 and forces it down; the first part of the movement brings the contacts 65^b and 65^c together, following which plates 65^a 15
are brought against the plate 65.

The switch arm 53 is, of course, insulated in any suitable manner so that when the switch is closed the current passes in through the contact 73^a and through plate 72^a to conductor 73 and then by connecting bolts 53^c to the plates 65^a and 65^d. Coming out 20
the current flows from the plate 65 to the conductor 65^a. The motor 64 is preferably mounted in a suitable box 82 which may be provided with a water tight cover 83 having 25
a hinge connection 82^a.

The switch 39 may be of any suitable construction such as that illustrated in Figs. 4 and 5 in which the lever 76 is rigidly attached to the shaft 75, said shaft 75 carrying contact arms 42 and 42^c, the former of which may strike either of the contacts 46 and 47, as described above; the latter of which is connected by a suitable flexible conductor 42^b with a terminal 42^d to which the conductor 48 attaches. When the lever 76 is thrown toward the right, the current passes in and through the instrument, by conductor 48, terminal 42^d, wire 42^c, arm 42^b, contact 47, wire 44^a, conductor 44 through 30
terminal 47^b. When thrown in the other direction, the current passes through the contact 46, wire 46^a to the terminal 46^b and thence by the wire 43.

The switch lever 76 is normally held in upright position, as shown in Fig. 4, by any suitable means. At the points 40 and 41, the circuit through the magnet 26 can be closed at will for which purpose a simple lever 40^a is provided which may connect the contacts 40^a and 40^b. A spring 40^b normally holds the switch arms 40^a in their open position. The contacts 40^c and 40^d are connected respectively with contacts 47 and 42^a by suitable conductors 47^a and 42^b, and this arrangement enables the whistle to be blown at will by electrical means from either end of the bridge. Evidently the same arrangement may be adopted to enable the whistle to be blown from any other point on the ship. 50
60

The parts at the switch lever 76 may be mounted in a suitable case 39^a. In order to hold the lever 76 in its neutral position, or in either of the whistling positions, the shaft 75 may be provided with a segmental star 65
65

wheel 77 having three notches 78, any one of which may be engaged by a roller 79 carried on a lever 80, which lever is pivoted at 81 and pulled toward the star wheel by a spring 82.

Evidently the conductors 42^b and 47^a from the control point 39 to the control points 40 and 41 constitute extensions of the circuit for blowing the whistle at will, and special attention is called to this arrangement which enables the whistle to be blown at will from different points, for instance, from the pilot house and from either end of the bridge. 70
75

Obviously, the hand operated means for actuating the whistle may be dispensed with if desired, without departing from the spirit of the invention. 80

It is understood that the embodiment of the invention described above is only one of the many embodiments my invention may take, and I do not wish to be limited in the practice of my invention, nor in my claims, to the particular embodiment set forth. 85

What I claim is;—

1. In a fluid operated signal apparatus, a whistle, valve-means for admitting the operating fluid thereto, hand operated means for actuating said valve-means, independent electrically controlled means for actuating said valve-means, a circuit through said electrically operated means, an electric motor, and a circuit therefor, a timing device controlling the opening and closing of said first named circuit, means for driving said timing device at a reduced rotary speed from said motor, and a hand operated switch member for simultaneously holding either of said circuits open and the other circuit closed. 90
95
100

2. In a fluid operated signal apparatus, a whistle, valve-means for admitting the operating fluid thereto, electrically controlled means for actuating said valve-means, a circuit through the same, automatic electrically operated means for periodically closing said circuit to blow the whistle, and a member for controlling said electrically operated means and for closing said circuit at will independently of said automatically operated means. 105
110
115

3. In a fluid operated signal apparatus, in combination, a whistle, a valve adapted to admit fluid thereto, a piston for actuating said valve, an auxiliary valve for admitting the operating fluid to said piston, a stem for actuating said valve, a hand operated lever for moving said stem to open said valve, an electro-magnet, an armature therefor, a member actuated by said armature for engaging said stem to actuate the stem independently of said lever, and means for closing a circuit through said electro-magnet. 120
125

4. In a fluid operated signal apparatus, in combination, a whistle, valve means for admitting operating fluid thereto, electrically 130

controlled means for operating said valve means, electrically controlled automatic means for actuating the same periodically, and a member for closing a circuit through said automatic means to sound the whistle automatically and for closing a circuit through said electrically controlled means to blow the whistle at will.

5. In a fluid operated signal apparatus, a whistle, valve means for admitting operating fluid thereto, a controlling switch lever having a normal position, and adapted to move in either direction from said normal position, electrically controlled means for actuating said valve means, means for closing the circuit directly through said electrically controlled means by moving said controlling lever in one direction, automatic electrically operated means for actuating said signal periodically, and means for closing a circuit therethrough by moving said controlling lever in the opposite direction.

6. In a fluid operated signal apparatus, a whistle, valve means for admitting the operating fluid thereto, electrically controlled means for actuating said valve means, a motor for actuating said valve means automati-

cally, a lever, means for closing a circuit to blow the whistle at will by the movement of said lever in one direction through said electrically controlled means, and means for starting the motor by the movement of the said lever in the other direction.

7. In a fluid operated signal apparatus, a whistle, valve means for admitting the operating fluid thereto, a circuit including electrically controlled means for actuating said valve means, a second circuit including electrically controlled automatic means for actuating the same periodically, and a switch member for mechanically opening the first named circuit through said automatic means to stop sounding the whistle automatically and for independently closing the said second circuit through said electrically controlled means to blow the whistle.

In testimony whereof I have hereunto set my hand in presence of two subscribing witnesses.

FRANK W. WOOD.
